(57) **CLAIM**

The ornamental design for an air nozzle, as shown and described.

DESCRIPTION

FIG. 1 is an oblique view of an air nozzle showing our new design;

FIG. 2 is a side elevation view thereof showing the back side;

FIG. 3 is side elevation view thereof, showing the front side;

FIG. 4 is a side elevation view thereof, showing the right side;

FIG. 5 is side elevation view thereof, showing the left side;

FIG. 6 is a top plan view thereof; and,

FIG. 7 is a bottom plan view thereof.

The broken lines showing the engagement mechanisms for engaging the air nozzle to an air blower and forms no part of the claimed design.

1 Claim, 4 Drawing Sheets
